(57) CLAIM

We claim the ornamental design for a detachable unit for portable computer, as shown and described.

DESCRIPTION

FIG. 1 is a front perspective view of a detachable unit for portable computer of the present invention;
FIG. 2 is a front view thereof;
FIG. 3 is a rear view thereof;
FIG. 4 is a first side view thereof;
FIG. 5 is a second side view thereof;
FIG. 6 is a top view thereof; and,
FIG. 7 is a bottom view thereof.

The broken lines shown represent unclaimed subject matter and form no part of the claimed design.
